DESIGN FOR A TOWEL HANGER OR SIMILAR ARTICLE

Michael Kiebzak, Buffalo, N. Y.

Application August 1, 1940, Serial No. 94,122

Term of patent 14 years

To all whom it may concern:

Be it known that I, Michael Kiebzak, a citizen of the United States, residing at Buffalo, in the county of Erie and State of New York, have invented a new, original, and ornamental Design for a Towel Hanger or Similar Article, of which the following is a specification, reference being had to the accompanying drawing, forming part thereof.

hanger or similar article showing my new design.

I claim:

The ornamental design for a towel hanger or similar article, as shown.

MICHAEL KIEBZAK.
